UNITED STATES PATENT OFFICE.

HARRY BARNARD AND JAMES R. CARDWELL, OF CHICAGO, ILLINOIS, ASSIGNEES TO UNION DRAFT GEAR COMPANY, OF CHICAGO, ILLINOIS, A CORPORATION OF DELAWARE.

DRAFT GEAR.

Application filed October 15, 1923. Serial No. 668,532.

The invention relates to draft gears for railway cars; its objects being to insure smoothness of action and certainty of release. 5 The gear is of the friction type and includes intercalating friction plates which are placed under compression by wedging elements. Two forms of embodiment of the invention are hereinafter described, and are 10 illustrated in the accompanying drawings, in which.

Fig. 1 is a central plan section of the gear, parts of the car structure being shown in elevation;

15 Fig. 2 is a central longitudinal vertical section of the gear, details of the coupler element being shown in elevation;

Fig. 3 is a view similar to Fig. 1, with the parts in different position, the friction spring and wedging elements being shown 20 in plan;

Figs. 4, 5 and 6 are details of parts of the gear;

25 Figs. 7 and 8 are views corresponding with Figs. 1 and 2, showing a modified form of construction.

At 10 there is shown a pair of center or draft sills; at 11, 11, a pair of draft lugs; at 12, 12, a pair of buffing lugs; at 13 the 30 butt end of a coupler, and at 14 the coupler extension or tail-strap, here shown as taking the form of the well known and commonly used yoke.

The followers 15, 16, for engaging, respectively, the draft and buffing lugs, are of chambered form, each having side walls, as 17, 18, and top and bottom walls, as 19, 20. The length of these several walls is such that when the gear is brought into full 40 compression, as shown in Fig. 3, those of the two followers meet and consequently form limiting stops.

Two groups, 21, 22, of intercalating friction plates are housed within the chambers 45 of the two followers, the outer plate of each group bearing against the side walls 17, 18. Engageable with the inner plate of each group are two pairs of friction shoes 23, 24, at one end of the gear, and 25, 26, at the 50 other end thereof. In the construction shown in Figs. 1, 2 and 3, these shoes have a direct bearing upon the followers, and each is provided on its inner face with a wedging surface 27, inwardly directed, that

is to say, facing toward the middle portion 55 of the gear. Cooperating with the wedging faces of each pair of shoes is a floating wedge-block 28, 29, and reacting between these two wedge-blocks is a spring 30 on the axis of the gear for resisting longitudinal 60 movement of the blocks by the action of either pair of advancing friction shoes.

Exterior of the spring 30 is a more powerful releasing spring 31, reacting between 65 spring seats 32, 33, one of which is shown in Fig. 5,—these seats being provided with rearwardly extending legs 34, 35, which have a direct bearing upon the adjacent follower.

Within the chamber of each follower 70 there is housed a pair of retracting bars 36, 37, for engaging shoulders formed on the friction plates 21, 22, to restore them to normal position upon the release of the gear after compression. These bars are engaged 75 and urged backwardly by lugs 38, 39, extending upwardly and downwardly from each of the friction blocks 28, 29.

Upon compression of the gear in buff 80 the follower 15 moves backwardly, carrying with it positively the shoes 23, 24, these shoes being urged outwardly by the wedging action of the block 28, the advance of which is resisted by the spring 30. Force transmitted through this spring urges backwardly 85 the block 29, spreading the shoes 25, 26. The follower coming into engagement with one set of the friction plates in each group carries them forwardly between the members of the other set, the latter being moved backwardly into contact with the follower 16, which arrests their further movement. 90

The spring 31 is also compressed by the 95 advance of the follower and the inward movement of the seat 32. Upon release the spring 31 returns the follower to its normal position, relieving the wedging compression upon the friction plates and permitting the shoes to return to normal position under the influence of the spring 30.

The releasing spring 31 being exterior of the wedge-resisting spring 30, the releasing action may be the much more powerful, thereby insuring certainty of release. The engagement of the friction shoes directly 105 with the followers insures smoothness of action as the gear compresses.

The action of the gear under the influence

of draft stresses is the same as in buffing, the parts, however, being moved in the opposite direction.

In the form of construction illustrated in Figs. 7 and 8, the spring arrangement of the construction already described is retained but the wedging elements are differently disposed. The friction shoes 40, 41, and 42, 43, are spaced apart from the end walls 10 of the followers and are provided with inwardly inclined wedging faces. A wedging element 44, 45, cooperates with the pair of shoes at each end of the gear and is seated against the end wall of the follower, and is 15 provided with forwardly projecting fingers, as 46, 47, against the ends of which the seats, as 48, for the releasing spring 31 bear. Spring seats 49, 50, for the inner spring 30 are provided with flanges, as 51, 20 which bear against the shoulders of the shoes, as 40, upon which their wedging faces are formed, and are also provided with upwardly and downwardly projecting fingers, as 52, 53, for engaging the plate re- 25 tracting bars 36, 37.

The two forms of construction, while desirable may be deviated from as to detail without departing from the scope of the invention.

30 We claim as our invention—

1. In a draft gear, in combination, a pair of opposed chambered followers, a pair of friction shoes seated against each follower at each end thereof and having inclined wedging faces, a group of intercalating friction plates between the wedging shoes at each side of the gear and the side walls of the followers, a pair of wedge blocks 35 engaging the wedging faces of the shoes at each end of said gear, an inner spring for resisting the inward movement of said shoes, and an outer spring for resisting the inward movement of said wedge blocks and for forcing the same outwardly upon release of the gear.

2. In a draft gear, in combination, a pair of opposed chambered followers, groups of intercalating friction plates cooperating with the side walls of the followers, wedge means for compressing the plates against such walls, a spring on the axis of the gear 50 cooperating with the wedge means, and a spring inclosing the first-named spring and reacting directly upon the followers.

3. In a draft gear, in combination, a pair 55 of opposed chambered followers, groups of intercalating friction plates cooperating with the side walls of the followers, wedge means for compressing the plates against such walls, a spring on the axis of the gear 60

cooperating with the wedge means, a spring inclosing the first-named spring and reacting directly upon the followers, and re- 65 tracting bars engageable with shoulders of each set of plates of both groups and by the first-named spring.

4. In a draft gear, in combination, a pair of chambered followers, friction and wedge elements inclosed within the followers, a pair of nested expansion springs located on 70 the axis of the gear, the inner spring cooper- 75 ating with the wedge elements and the outer spring reacting directly upon the followers.

5. A shock absorber comprising a plurality of sets of friction plates which are slide- 80 able lengthwise relatively to each other, and the plates of one set alternating with another, a plurality of buffing members each 85 engaging the outer ends of the plates of one set and also supporting said plates on one longitudinal side thereof, a plurality of wedge plates each engaging the opposite longitudinal side of said plates, a plurality of longitudinally movable wedge blocks 90 each having wedging engagement with one of said wedge plates and each provided with inwardly extending fingers, spring means engaging said fingers for releasing the wedge action of said wedge plates and blocks.

6. A shock absorber comprising a plurality of sets of cooperating friction plates which alternate with each other and are capable of sliding lengthwise relatively to one another, a plurality of buffer members 95 supporting said plates on one of their longitudinal sides and also adapted to engage the outer ends of the same, a plurality of wedge plates each engaging with the opposite longitudinal side of said friction plates, a plurality of longitudinally movable wedge blocks 100 each having wedging engagement with one of said wedge plates and each provided with inwardly extending fingers, spring means engaging said fingers for moving said blocks in the direction for re- 105 tracting the same from said wedge plates, means for resisting the inward movement of said wedge plates, said means comprising a spring seat for engaging said plates, spring means for engaging said seats, and means 110 operated by said spring seats for retracting said plates after compression.
